UNITED STATES PATENT OFFICE.

LESTER C. BEARDSLEY, OF CLEVELAND, OHIO.

DESIGN FOR A CAMPAIGN-TORCH.

SPECIFICATION forming part of Design No. 18,715, dated November 6, 1888.

Application filed August 2, 1888. Serial No. 281,823. Term of patent 3½ years.

To all whom it may concern:

Be it known that I, LESTER C. BEARDSLEY, a citizen of the United States, residing at Cleveland, in the county of Cuyahoga and State of Ohio, have invented a new and original Design for a Campaign-Torch, of which the following is a specification.

The nature of my design is fully shown in the accompanying drawing.

- 10 The design consists in a torch the body of which has the form and configuration of an H-shaped body provided with a vertical projection at the top, as shown in the drawing.

A B are two upright parts joined at their middle by a suitable connection, C. The parts A 15 B are made square in their general contour and present the appearance of a block letter.

I claim—

The design for a campaign-torch herein shown and described, consisting of the H- 20 shaped body provided with a vertical projection at the top.

LESTER C. BEARDSLEY.
